tion of Delaware

Application February 14, 1933, Serial No. 656,682

15 Claims. (Cl. 93—94)

This invention relates to the manufacture of paper tubes for shot shell bodies, and contemplates certain improvements in the matter of penetrating said tubes with a waterproofing material. The present application is a continuation-in-part of the inventor's prior application, Serial No. 527,506, filed April 3, 1931.

Shot shell tubes are wound from a specially prepared paper which is of a somewhat porous texture. The paper is ordinarily supplied in sheets of a length corresponding to the length of five shot shell bodies and of the width necessary to supply about four-and-one-half wraps of paper in a tube of the desired diameter. Each tube or shell body thus comprises four to four-and-one-half layers of paper, secured together with a suitable adhesive, such as starch. The edge of the sheet which is to form the outside of the tube is usually colored with a suitable coloring material and is preferably formed of a separate layer. The entire sheet may be built up of as many as five separate layers of pulp, and the layer which forms the outside wrap and receives the coloring matter is made from a finer grain fibre which produces a more dense paper. The outer part or section of the outside wrap of each tube is thus much more dense and less permeable than the remainder of the tube.

In preparation for use such tubes are usually coated with a heat absorbent, such as paraffin wax, castor oil or other suitable material, which penetrates the paper and prevents burning and charring thereof during the combustion of the shot propelling powder. When a shot shell is fired the combustion of the powder produces for a brief interval a condition of a high temperature and high pressure, and burning powder grains moving at high velocity will penetrate and char dry paper to such an extent that the shell body is greatly weakened, and may be ruptured either in firing or upon subsequent extraction from the gun chamber. It is highly important that shot shells be protected against such charring.

A common method of treatment for this purpose consists in immersing the tubes in a bath of the heat absorbent such as paraffin at a temperature well above the boiling point of water. In order to secure the proper penetration, the tubes as placed in the heated bath contain about 8% of moisture, part of which is in the fibres themselves, and the remainder in the inter-fibre spaces. Due to the heat of the bath this moisture is vaporized, and is expelled along with a quantity of air, both the air and the water being replaced by the heat absorbent. Due to the greater

density of the outside surface of the tube, the penetration of the heat absorbent is chiefly from the ends and the interior surface, water vapor and air being expelled through the relatively dense exterior surface as the heat absorbent penetrates from the interior. This process is very readily observed when the tube is placed in a heat absorbent bath within a glass container; gas bubbles collect on the exterior surface in increasing quantities and are eventually released and rise to the surface of the bath.

As heretofore stated, coloring matter is usually applied to the relatively dense portion of the sheet which forms the tube exterior. If this coloring matter is a dye, it may not substantially increase the density of the sheet or interfere with the passage of air and water vapor therethrough. However, some colors can be secured only by the use of pigments. For example, a desirable and permanent green is best obtained from a mixture of Prussian blue and yellow chrome. If the desired color can be secured only by the use of a pigment, such a pigment acts to further increase the density of the already comparatively dense outside surface with the result that the passage of air and water vapor therethrough in the operation of applying the heat absorbent is prevented or greatly retarded. It thus becomes very difficult to properly impregnate with a heat absorbent a tube having a pigment in its surface. Usually only the inside wrap of paper is penetrated, the rest of the wall remaining dry. The expansion of the imprisoned gases may even buckle the inside wraps of paper, forming an inwardly projecting ridge, and rendering the tube useless. The fact that this difficulty is due to the failure of the air and water vapor to be expelled through the pigmented surface has been demonstrated by slightly abrading parts of the surface or perforating them with a sharp implement. The air can be seen to escape through such an abraded or perforated surface with an accompanying increased penetration by the heat absorbent.

It is an object of this invention to provide a suitable means for permitting the escape of air and water vapor from a shell body the exterior surface of which contains a pigment or is for any other reason of such a density as to interfere with the escape of air and water vapor, while leaving the tube in sections each having a continuous impervious and unabraded surface.

It has been found that the provision of a small number of gas passages, in the form of isolated breaks, cuts, perforations or abrasions, spaced

and separated by substantial areas of the unbroken and impervious surface, enables the requisite escape of gases, and insures adequate penetration of the tube by the heat absorbent.

5 Such gas passages may be spaced substantial distances, and each may consist of a single cut or abrasion, or a line or group of small cuts, perforations or abrasions. Whether arranged singly or in groups, the gas passages are preferably located on or adjacent to the lines on which the tube is to be cut to form separate shell bodies. It is a surprising fact that the provision of a very small number of isolated perforations or groups of perforations, separated by relatively 10 large impervious areas, enables the escape of gases from the entire tube wall, and insures effective and uniform absorption of paraffin or other treating fluid. An unperforated tube which has been given the usual paraffin treatment when 15 cut open shows a fair penetration of the inner wrap only and the end portions only of the other wraps, the remainder of the tube paper being substantially dry, whereas a tube with a few isolated cuts or abrasions is thoroughly permeated.

20 25 In the drawing:

Fig. 1 is a perspective of a tube embodying one form of the invention.

Fig. 2 is a perspective of a tube including a slightly different embodiment of the invention.

30 Fig. 3 is a plan view of a sheet of the type used in rolling the tube of Fig. 2, the colored portion of the sheet being shaded.

Fig. 4 is a perspective of a tube embodying another form of the invention.

35 Fig. 5 is a fragmentary diagrammatic showing of one form of mechanism which may be utilized in the practice of the invention.

Fig. 6 is a fragmentary diagrammatic showing of an alternative mechanism for use in the 40 practice of the invention.

In Figs. 1 and 2 the gas passages in the tube 10 are in the form of lines of small perforations 11 extending circumferentially of the tube, and preferably on the lines on which the tube is to 45 be cut. Any convenient or desired number of such lines of perforations may be provided; two lines, each spaced from the adjacent end of the tube by the length of two shell bodies, as shown in Fig. 1, are adequate; although four lines, 50 separating the tube into shell body lengths 13 (Fig. 2) may be used. Such perforations may be formed in various ways; one method comprises the application of a knurling wheel or wheels to the sheet 14 (Fig. 3) from which the 55 tube is rolled, and particularly to the colored portion 15 of the sheet, which portion forms the outside surface wrap of the tube.

Fig. 4 illustrates a tube in which each isolated 60 gas passage is a single cut, slot or abrasion 16 on one side of the tube. One method of forming such abrasions or cuts is to bring a cutting tool or tools against the tube while the tube is suitably held. If the tube is supported on an 65 arbor 12 (Fig. 5) it may be cut or "nicked" by the mere pressure of a cutting blade 17 which does not move transversely of the tube surface. For this purpose, the usual tube cutting knives 70 may be utilized, neither the tubes nor knives being rotated while the knives are brought against the tube. However, it is sometimes convenient to support the tubes in a substantially semi-cylindrical trough 18 (Fig. 6), and to use one or more rotating cutters to form the gas 75 passages, the tube being held against rotation by

friction with the trough, assisted if desired by such means as a spring finger 20.

The present invention is believed to comprise the first discovery that gases can be expelled from a substantial area of a tube or sheet by the use of small, widely spaced perforations, and the appended claims are to be broadly construed.

What is claimed is:

1. In the manufacture of shot shell tubes, the method of permeating the tube walls with a heat 10 absorbent which comprises the provision of transversely extending lines of perforations in the exterior surface of the tube for permitting the escape of gases during the application of the heat absorbent.

2. In the manufacture of impregnated paper articles having one relatively dense surface, the method of providing for the escape of gases during the impregnating operation which comprises the provision of segregated groups of perforations 20 in said dense surface.

3. In the manufacture of impregnated shot shell tubes having a relatively dense exterior surface, the method of providing for the escape 25 of gases during the impregnating operation which comprises the provision of segregated groups of perforations in said dense exterior surface.

4. In the manufacture of impregnated paper articles having one pigmented surface, the 30 method of providing for the escape of gases during the impregnating operation which comprises the provision of segregated groups of perforations in said pigmented surface.

5. In the manufacture of impregnated shot shell tubes, the method of providing for the escape 35 of gases during the impregnating operation which comprises the provision of segregated groups of perforations in one surface of said tubes.

6. In the manufacture of shot shell tubes impregnated with a heat absorbent, the method of increasing the penetration of the tube wall by such heat absorbent which comprises the provision of transversely extending lines of perforations in one surface of said tube.

7. In the manufacture of paper articles impregnated with a heat absorbent, the method of increasing the penetration of the article by such absorbent which comprises the provision of segregated groups of perforations in one surface of 50 said article.

8. A sheet of paper for the manufacture of a shot shell tube comprising a pigmented surface for forming the exterior of said tube and groups of segregated perforations in said pigmented surface.

9. In the manufacture of shot shell tubes, the method of permeating the tube walls with a heat absorbent which comprises the provision in the surface of the tube of relatively small openings 60 separated by relatively large impervious areas, said openings permitting the escape of gases during the application of the heat absorbent.

10. In the manufacture of impregnated paper articles having one relatively dense surface, the 65 method of providing for the escape of gases during the impregnating operation which comprises the provision of spaced openings in said dense surface, said openings being separated by relatively large impervious areas.

11. In the manufacture of impregnated shot shell tubes having a relatively dense exterior surface, the method of providing for the escape of gases during the impregnating operation which comprises the provision of spaced openings in 75

- said dense exterior surface, said openings being separated by relatively large impervious areas.
12. In the impregnation of a paper article with a fluid medium, the method of providing for the escape of gases from the article during the impregnating operation which comprises the provision in one surface of the article of a relatively small opening or abrasion surrounded by a relatively large impervious area.
- 10 13. In the impregnation with a fluid medium of a paper article having one relatively dense surface, the method of providing for the escape of gases during the impregnating operation which comprises the provision in said dense surface of 10 a perforation breaking the continuity of said surface and surrounded by a relatively large unbroken and impervious area.
14. In the impregnation of paper articles with a fluid medium, the method of increasing the penetration of the articles by the medium which comprises the provision of spaced opening in one surface of such articles, said openings being separated by relatively large impervious areas.
15. In the manufacture of rolled paper tubes adapted to be impregnated with a fluid medium, the method of forming spaced openings for the escape of gas during the impregnating operation which comprises applying spaced abrading tools to the tube while the tube is held against rotation.
